UNITED STATES PATENT OFFICE.

JOHN G. SCHLENTER, OF TOLEDO, OHIO.

CLOTHES-LINE FASTENER.

No. 899,566.

Specification of Letters Patent. Patented Sept. 29, 1908.

Application filed November 25, 1907. Serial No. 403,676.

To all whom it may concern:

Be it known that I, JOHN G. SCHLENTER, citizen of the United States, residing at Toledo, in the county of Lucas and State of Ohio, have invented certain new and useful Improvements in Clothes - Line Fasteners; and I do hereby declare the following to be a full, clear, and exact description of the invention, such as will enable others skilled in 10 the art to which it appertains to make and use the same.

This invention relates to improvements in clothes-line fasteners of that class in which the line is directed over one end of a pivoted 15 lever and securely gripped by the opposite end thereof.

The invention has for its object to provide a simplified and improved construction whereby the cost of manufacture is reduced 20 to a minimum, the device comprising two simple castings which after being coated with a rust resisting material are in readiness to be assembled for the market.

The invention embodies certain novelties 25 of construction and the details and arrangement of parts hereinafter shown, described and specifically claimed.

In the accompanying drawings Figure 1 is a perspective view showing the application 30 of the device; Fig. 2 is a front view in enlarged detail of the complete fastener; Fig. 3 is a side elevation of the same, the supporting body plate for the pivoted lever being in vertical section; and Fig. 4 is a rear view of 35 the supporting plate.

Referring to the details, 1 is a cast metal 40 body plate adapted to be secured to a support and the same is provided with a slot 2 entering from the top margin and extending to approximately the center of the body plate, and 3 and 4 are indentations in the rear face of the plate 1 on opposite sides of the slot 2. The indentations 3 and 4 are adapted to receive laterally extending lugs 5 and 6 45 on opposite sides of a lever 7, the upwardly extending arm 8 of which is provided at its end with a notch 9 through which a line is directed, the downwardly extending arm 10 being adapted to clamp and firmly hold the

line between it and the plate 1 adjacent to 50 the pivotal connection of the lever with the plate.

11 is a supplemental hook upon the lever 7, the same extending directly outward from the pivotal connection of the lever with the 55 plate 1 and serving as an attaching means for a line where the latter is secured at a plurality of points. By providing the hook upon the lever at a point directly outward from the pivotal connection of the lever, the 60 operation of the lever as a fastener is not interfered with, as will be apparent.

In assembling the device, the lever 7 is directed through and along the slot 2, as indicated in dotted lines, Fig. 3, to cause the lugs 65 5 and 6 to seat in the indentations 3 and 4. When the two parts are thus assembled the plate 1 is secured to a support and the lever is then secure from detachment.

It is thus seen that the device consists of 70 two simple castings capable of being assembled in pivotal relation without the requirement of any machine work thereon.

The operation of the device as a fastening 75 means for a clothes-line will be understood from the drawings when taken with the foregoing description.

Having described my invention, what I 80 claim and desire to secure by Letters Patent, is:—

In a clothes-line fastener, a body plate 85 having a slot extending into the margin thereof and provided with indentations in its rear face on opposite sides of the slot, and a lever provided at a central point with oppositely extending lateral lugs adapted to seat in said indentations, the upper arm of said lever being adapted to guide a line and the lower arm to clamp the line against the body plate, and a hook upon the lever extending 90 directly outward from the lugs thereon, substantially as described.

In testimony whereof, I hereunto affix my signature, in presence of two witnesses.

JOHN G. SCHLENTER.
